UNITED STATES PATENT OFFICE

133,035

DESIGN FOR A REGISTER UNIT

Samuel Greenberg, Chicago, Ill., assignor to Automatic Gas-Lok Mfg. Co., Chicago, Ill., a co-partnership composed of Samuel Greenberg, Miriam Greenberg, and Herbert J. Greenberg

Application September 24, 1941, Serial No. 103,465

Term of patent 7 years

To all whom it may concern:

Be it known that I, Samuel Greenberg, a citizen of the United States and a resident of Chicago, in the County of Cook and State of Illinois, have invented a new, original, and ornamental Design for a Register Unit, of which the following is a specification, reference being had to the accompanying drawing, forming a part thereof, and in which:

Fig. 1 is a front elevational view of a register unit showing my new design;

Fig. 2 is a rear elevational view of the same;
Fig. 3 is a side elevational view of the same as seen from the right in Fig. 1; and

Fig. 4 is an elevational view of the same as seen from above in Fig. 2.

I claim:

The ornamental design for a register unit, as shown.

SAMUEL GREENBERG.
